UNITED STATES PATENT OFFICE.

LOUIS S. FLATAU, OF ST. LOUIS, MISSOURI, ASSIGNOR TO JOSEPH W. LEWIS, OF ST. LOUIS, MISSOURI.

CUP-DISPENSER.

1,096,499.

Specification of Letters Patent. Patented May 12, 1914.

Application filed June 30, 1913. Serial No. 776,692.

To all whom it may concern:

Be it known that I, LOUIS S. FLATAU, a citizen of the United States of America, and resident of the city of St. Louis and 5 State of Missouri, have invented certain new and useful Improvements in Cup-Dispensers, of which the following is a full, clear, and exact description, reference being had to the accompanying drawings, forming a 10 part of this specification.

My invention relates to a device for dispensing paper drinking cups, and the invention has for one of its objects to provide efficient means by which the cups nested together, may be separated for discharge from the dispenser.

Another object of the invention is to provide a receiver into which each cup is deposited when separated from the remaining 20 nested cups, and means for operating said receiver to discharge the cup therein while the cup to be next deposited in the receiver is being separated from the collection of nested cups to enter the receiver.

25 A still further object of my invention is to provide a novel form of coin controlled mechanism for restraining the cup separating mechanism from movement pending the deposit of a coin by which the coin controlled mechanism is rendered inactive.

Figure I is a vertical section through my cup dispenser. Fig. II is a vertical section through the dispenser, taken on a line at a right angle to that on which the section in 35 Fig. I is taken. Fig. III is a top or plan view of the cup separating mechanism of my dispenser, the housing for such mechanism being shown in horizontal section. Fig. IV is a vertical section taken on irregular line IV-IV, Fig. III. Fig. V is a section of the coin controlled device. Fig. VI is a perspective view of the latch dog of the coin controlled mechanism, the dog being shown inverted. Fig. VII is an enlarged view of a plurality of nested cups, and the cup separators in normal positions. 45 Fig. VIII is a view similar to Fig. VII, with the cup separators in the positions assumed when a lowermost cup is being separated from the nested cups above it. Fig. IX is an enlarged perspective view of one of the cup separators. Fig. X is a view similar to Fig. III illustrating a modification. Fig. XI is a vertical section of the modified 55 construction. Figs. XII and XIII are per-

spective views of the separators of the modification.

In the drawings, A designates a series of paper cups nested together, each cup being provided at its mouth with an annular lip a.

60 1 designates the magazine of my dispenser, within which the nested cups A are housed, this magazine being preferably of glass, or other transparent material, in order that the cups may be viewed through the 65 magazine. The magazine is supported by a housing 2, which includes a cover 3 on which the magazine rests. Within the housing beneath the cover 3 is an annular shelf 4, provided with a downwardly extending tubular 70 neck, and at the lower end of the housing is a discharge spout 6.

75 The neck 5 within the housing provides a passageway through which the cups A may descend singly when separated from the others with which it is nested, and beneath said neck 5 is a tiltable cup receiving barrel 7, supported in the housing 2 by trunnions 8 mounted in members 9 and 10, (see Fig. II) 80 parallel with the sides of the housing 2. The cup receiving barrel has a peripheral opening 7' adapted to register with the neck 5 to permit the deposit of cups into the barrel from the magazine 1, and the escape of cups from the barrel to the discharge spout 6. 85 Within the barrel 7 is an upwardly extending post 11, around which the cups are deposited so that they will be positioned opposite the opening 7', as seen in Figs. I and II, ready for discharge from the barrel 90 to the discharge spout 6 when the barrel is tilted. The cup receiving barrel is illustrated in Figs. I and II in its normal position, and the barrel is automatically returned to such normal position after being 95 tilted for the discharge of the cups, by a counterbalance weight 12 at the bottom of the barrel.

I will now proceed to a description of my cup separating mechanism which is shown 100 most clearly in Figs. III, IV and VII to IX, inclusive. This mechanism is located within the housing 2, and includes an oscillatory shifter B which comprises a central ring 13 loosely fitted in the neck 5 extending downwardly from the shelf 4, and a flange 14 extending outwardly over said shelf from said ring. The ring 13 of this shifter is in registration with the magazine 1 to provide 105 for the descent of cups to and through said 110

ring from said magazine. The shifter B is provided with a handle 15 which extends through a slot 2' in the housing 2, this handle normally occupying the position in which it is seen in Fig. III, and being movable in the direction indicated by the arrow for the operation of the cup separators about to be described.

The oscillatory shifter B carries a fork 16, (see Figs. I and II and dotted lines Fig. III), which straddles a pin 17 extending from one of the side walls of the cup receiving barrel 7. This fork 16, by co-operation with the pin 17, acts to tilt the cup receiving barrel upon movement of the shifter B, so that a cup therein will be discharged through the peripheral opening 7' in the barrel into the discharge spout 6. When the handle 15 of the ejector operating device is released, the cup receiving barrel is returned to its normal position under the influence of the counterbalance weight 12, and the pin 17 and fork 16 act to return the shifter B to its normal position, seen in Fig. III.

18 and 19 are screw posts fixed to the shelf 4 within the housing 2 and extending vertically therefrom, the screw posts 18 having right hand screw threads, and the screw posts 19 having left hand screw threads. By reference to the drawing it will be seen that the posts having similar threads are diametrically opposite each other within the housing 2, they being so disposed with an object in view that will be fully understood from the description that is to follow.

C and C' are cup separators, operable, respectively, upon the screw posts 18 and 19. Each separator C or C' comprises a body 20 having an internal thread suitable for operation upon the screw post the separator is applied to. The body of each separator carries a lower wing 21, and an upper wing 22 arranged in different vertical planes, both of which are adapted to be placed in engagement with the lips a of the cups A by passing through slots 18' in the ring 13. The separators C and C' are provided with slotted arms 23, in which vertical pins or studs 24, 25 carried by the horizontal flange of the shifter B are operable. As shown in the drawings, the studs 24 for operating the separators C are located beneath the flange of the shifter B, and the studs 25 for operating the separators C' are located above said shifter, this arrangement being followed in order that, when the shifter B is operated by its handle 15, the separator C on the screw posts 18 having right hand threads may move downwardly and the separators C' may move upwardly on the posts 19 having right hand threads.

In the practical use of my cup dispenser, the operation is as follows: The separator shifter B normally occupies the position seen in Fig. III and when the shifter is in

this position, the lowermost wings 21 of the separators C and C' are all projected to the interior of the ring 13 of the shifter B where serve as rests or supports for the stack of nested cups in the dispenser as seen in Fig. VII. When the handle 15 of the separator shifter B is moved in the direction of the arrow Fig. III, the studs 24, 25 carried thereby are all moved in a circular path, and act to impart partial rotation in the same general direction to the several separators C and C'. The separators C on the posts 18, having right hand threads, are moved downwardly on said posts during rotation, and the separators C' on the posts 19, having left hand screw threads, are moved upwardly on these posts, while rotating thereon. As these movements of the separators C, C' occur, the cup supporting wings 21 of the separators C are moved in arcs of circles to carry them outwardly from positions beneath the mouth lip of the lowermost nested cup A. The upper wings of the separators C being offset into vertical planes different from the vertical planes in which the lower wings 21 are present from time to time, pass into the space between the mouth lip of the lowermost cup and the mouth lip of the cup next thereabove. Concurrently with the described movements of the separators C, the separators C' are rotated to such degrees as to remove their lower wings 21 from positions beneath the mouth lip of the lowermost cup and position the upper wings 22 of said separators between the mouth lips of the lowermost cup and the cup next thereabove. Continued movements of the separators C C', through the medium of the separator shifter B, results in continued rotative movements of all of the separators, with their upper wings 22 interposed between the mouth lips of the two lowermost cups. The movement of the shifter B and the separators has at this time been only partial, and continued movements of these parts results in the separator C continuing to travel downwardly in the posts 18, while the separators C' continue to travel upwardly on the posts 19. The obvious result is that the wings 22 of the separators C press downwardly upon the mouth lip of the lowermost cup, while the wings 22 of the separator C' press upwardly against the mouth lip of the cup next thereabove to lift it and the nested cups surmounting it. The travel of the separators C and C' in opposite directions, as stated, is sufficient to withdraw the lowermost cup from frictional engagement with the cup immediately above it and said cup is, therefore, permitted to fall from the cups above it, which are at this time supported by the upper wings 22 of the separators. During the movement of the shifter B, the cup receiving barrel 7 is tilted through the medium of the fork 16 and

the pin 17 from the position shown in Figs. I and II until the cup A, previously deposited therein, is ejected through the peripheral opening 7' of the barrel into the discharge spout 6; and when the cup-separated from the nested cups, as described, descends to the barrel, it is deposited on the periphery of said barrel to remain thereon until the barrel resumes its normal position 10 and the cup is permitted to fall through the peripheral opening 7' into the barrel, ready for ejection upon the next operation of the machine. Concurrently with the return of the cup receiving barrel to its normal position, accomplished through the medium of the counterbalance 12, the separator shifter B is rotated backwardly through the medium of the pin 17 and fork 16, and the separators C and C' are returned to their 15 normal positions, the separators C moving upwardly and the separators C' moving downwardly on their posts until the lower wings 21 of the several separators are brought to rest beneath what is then the 20 lowermost cup A.

I will now proceed to a description of the coin controlled mechanism of my dispenser.

26 designates a coin chute surmounting the cover of the housing 2, (see Figs. I, II, 30 and V), this coin chute being provided with a hollow base 27 secured to said cover. 28 is a latch dog having one of its ends pivotally attached to the base of the coin chute by a pin 29. This latch dog is provided with 35 a coin slot 30 located beneath the coin chute 26. At the free end of the latch dog is a downwardly extending tooth 31, preferably bifurcated, as seen in Fig. VI, to permit coins to enter thereinto. In the separator 40 operating shifter B is a slot 32, which is normally out of registration with but is adapted to be brought into registration with a slot 4' in the shifter supporting shelf 4. The separator operating shifter is provided with 45 a vertical abutment 33, which is so located thereon as to be slightly separated from the tooth 31 of the latch dog when the shifter is in its retracted and normal position.

50 It will be understood from the foregoing description that the latch dog 28 is normally so disposed that only a slight movement can be imparted to the shifter B before the abutment 33 of the shifter strikes against the 55 tooth 31 of said dog, and it is to be noted in this connection that such movement is insufficient to withdraw the lower cup supporting wings 21 of the separators C, C' from cup supporting positions. When, however, 60 a coin is dropped into the coin chute, it passes partially through the slot 30 in the latch dog and into the slot 32 in the shifter B to rest on the shelf 4; and upon movement being imparted to said shifter, the 65 coin rides beneath the latch dog, elevating it

sufficiently to raise the tooth of the dog above the abutment 33 of the shifter, after which the shifter is free to be moved the remaining distance for the operation of the cup separators C, C', as previously explained. During the movement of the shifter after the movement of the latch dog to inactive position, the coin is carried to the slot 4' and falls into a coin receptacle shown in Fig. II.

In the modification shown in Figs. X to XIII, inclusive, 2^a designates the dispenser housing, within which is a shelf 4^a serving to support the cup separators and the means for operating said separators. 14^a is a separator operating ring loosely mounted on the shelf 4^a and provided with a handle 15^a operable in a slot in the housing 2^a. The separator operating ring is provided near its inner marginal edge with slots 14^b and 14^c, 75 to permit of rotative movement being imparted to the separator operating ring without interference being offered to such movement by said posts. C^a are cup separators rotatable on the posts 18^a and having wings 90 22^a, the separators being provided with slotted lever arms 23^a, receiving studs 24^a carried by the separator operating ring 14^a, through the medium of which the separators C^a are connected to the separator operating 95 ring to provide for the operation of the separators. It is well to here note that the wings 22^a of the separators C^a are normally retracted from the path of movement of the nested cups in the dispenser, and are moved into engagement with the lips of the cups after a partial movement of the separator operating ring 14^a. C^b designates separators 100 rotatably fitted to the posts 19^a and located intermediate of the separators C^a. The separators C^b are provided with lower and upper cup engaging wings 21^b and 22^b arranged thereon in a manner similar to the arrangement of the wings 21 and 22 of the separators C^a in the first described construction, 105 these wings having offices similar to the wings 21 and 22 of the first described separators. The separators C^b are designed to partake of movements similar to those partaken of by the separators C^a; that is to say, 110 they are rotatable and movable in an upward direction when they are operated by the separator operating ring 14^a. The rotative movement of these separators C^b is accomplished through the medium of slotted lever arms 23^b, in engagement with studs 25^b carried by the separator operating ring. To provide for upward movements of the cup separators C^b during their rotative movements, each separator is positioned above 115 a cam post 34, having inclined runways 35, the functions of which are similar to the screw threads on the posts 19 of the first described construction. The separators C^b are 120 provided at their lower ends with cams 36 125 130

operable on the inclined cams 35. The separators C³ normally occupy the positions in which they are seen in Fig. X, and their wings 21^b are at this time in the path of travel of the cups in the dispenser so that they serve to support said cups.

From the foregoing, it will be understood that upon rotative movement being imparted to the separator operating ring 10 14^a, the separators C² and C³ will be rotated on their axes, the former merely rotating the latter partaking of upward movements in addition to their rotative movements. The wings 22^a of the separators C² pass between 15 the lip of the lowermost cup and the cup next thereabove, while the lips 21^b are being removed from positions beneath the lip of the lowermost cup, and the lips 22^b of the separators C pass between the lips of the 20 two lowermost cups. Then, upon continued movements of the separators through the medium of the separator operating ring, the separators C³ continue to rise and elevate the cups above the lowermost one, the latter 25 being restrained from upward movement due to the presence of the lips of the separators C² above said lowermost cup. As a consequence, the lowermost cup is separated from the cups above it, and may fall therefrom. A reverse movement of the separator 30 operating ring causes the separators to be returned to their normal positions, the wings 21^b of the separators C³ being first positioned beneath the lip of what is now the 35 lowermost cup and the wing of the separator C² being withdrawn from engagement with the cups.

I claim:—

1. In a dispenser, a magazine for holding 40 articles to be dispensed, two rotatable article separating devices for engagement with the articles to be dispensed, one of said devices being movable longitudinally of its axis to move the article engaged thereby 45 relative to the article engaged by the other separating device.

2. In a dispenser, a magazine for holding 50 the articles to be dispensed, a post having an inclined runway, a device for engagement with the articles to be dispensed movable on said inclined runway, and a second device engaging another of the articles to restrain it from movement in the direction of travel of the first mentioned device.

55 3. In a dispenser, a magazine for holding articles to be dispensed, a support for said magazine, a right hand screw threaded post on said support, a left hand screw threaded post on said support, separators for en-

gagement with the articles to be dispensed 60 operable on said screw threaded posts, and means for operating said separators.

4. In a dispenser, a magazine for holding articles to be dispensed, a support for said magazine, a right hand screw threaded post 65 mounted on said support, a left hand screw threaded post mounted on said support, separators for engagement with the articles to be dispensed operable on said screw threaded posts, each of said separators including a pair of article engaging wings arranged in different horizontal planes, and means for operating said separators.

5. In a dispenser, a support, two posts extending upwardly from said support, means 75 rotatable on said posts comprising members for engagement with adjacent articles to be dispensed, one of said means being movable longitudinally of its axis in one direction, and the other means being movable longitudinally of its axis in the opposite direction.

6. In a dispenser, a magazine for holding the articles to be dispensed, a vertically movable device adapted to lift the articles in said magazine, and a rotatable device adapted to restrain one of the articles from moving with the remaining articles.

7. In a dispenser, a magazine for holding the articles to be dispensed, a post having an inclined runway, a device for supporting 90 the articles to be dispensed movable upwardly on said inclined runway, and a second device adapted to engage one of the articles to restrain the latter from moving with the remaining articles.

8. In a dispenser, a magazine for holding the articles to be dispensed, vertically movable devices each having a wing for supporting said articles and a wing for lifting said articles; and rotatable devices 100 co-operative with said vertically movable devices, the said rotatable devices having a wing adapted to engage one of said articles to restrain the latter from upward movement.

9. In a dispenser, a magazine for the articles to be dispensed, a tiltable barrel open to receive the articles discharged from said magazine, a weight tending to hold said barrel in its normal position, and a shifter for tilting said barrel to discharge the articles 110 therefrom, the said barrel being provided with a projection and the shifter being provided with a fork straddling said projection.

L. S. FLATAU.

In the presence of—

E. B. LINN,
E. CLARK.
